C. D. TUSKA,
CONDENSER,
APPLICATION FILED MAR. 29, 1919.

1,371,061.

Patented Mar. 8, 1921.

UNITED STATES PATENT OFFICE.

CLARENCE D. TUSKA, OF HARTFORD, CONNECTICUT.

CONDENSER.

1,371,061.

Specification of Letters Patent.

Patented Mar. 8, 1921.

Application filed March 29, 1919. Serial No. 286,190.

To all whom it may concern:

Be it known that I, CLARENCE D. TUSKA, a citizen of the United States, residing at Hartford, in the county of Hartford and 5 State of Connecticut, have invented certain new and useful Improvements in Condensers, of which the following is a specification.

This invention relates to condensers. A 10 condenser involving the invention may be employed with utility in various ways in the electric and allied arts, although in practice it has demonstrated particular advantage as part of the equipment of a 15 wireless telegraph station. I have several objects in view, among the principal of them being the provision of an appliance of the character set forth, which is capable of inexpensive production, 20 without in any wise affecting its proper action. The device is comparatively light, yet strong, and it can be readily and easily operated to adjust or regulate its capacity. It may be constructed in various ways. In 25 the drawings accompanying and forming part of the present specification, I have illustrated somewhat fully and will hereinafter describe in detail several of the many forms of the invention. This disclosure is pri- 30 marily made to enable those skilled in the art to practise the invention. I am not restricted thereto. I may in fact depart therefrom in several particulars within the scope of the invention defined by the claims fol- 35 lowing said description.

Referring to said drawings—

Figure 1 is a top plan view of a condenser involving the invention.

Fig. 2 is an elevation of the same.

Fig. 3 is a transverse section of the body 40 part of the condenser.

Fig. 4 is a detail in sectional elevation, of the lower part of the condenser with several plies folded back and partly broken 45 away.

Fig. 5 is a plan view of another form.

Fig. 6 is an elevation of the same.

Fig. 7 is an elevation of a further form 50 of condenser.

Like characters refer to like parts throughout the several views which are on 55 different scales.

The condenser involves in its makeup at least two elements which are relatively adjustable to vary capacity. This relative adjustment, as will be inferred, may be ob-

tained in various ways. Usually, it is accomplished by the adjustment of one of the members or elements with respect to the other, yet this may not be necessary in all 60 cases. At least one or both of these elements comprises a plurality of portions desirably flexible. For illustration, I have obtained excellent results by making one portion, that is the insulating portion of some flexible 65 material such as paper stock of which there are several kinds. I might note at this juncture that paper sheet material or thin board answers quite satisfactorily indeed. Likewise, the conducting part or por- 70 tion of each element may vary. Satisfactory results have been obtained by the utilization of foil, such as tin-foil. Each portion or part, therefore, of each member or element, as I have considered the same, of 75 the condenser is thus flexible.

With the foregoing observations, I will now describe more definitely the structure shown, and will first refer to the illustration made by Figs. 1 to 4 inclusive. There is a 80 support or base which may also vary. That shown is denoted by 2 and is in the form of a disk of wood or other proper substance. The base or support has as shown fastened to its upper surface centrally thereof the 85 disk 3, the screw 4 being shown to hold said disk to the support 2.

The body of the condenser illustrated in these four views, which I am now specifically describing, is in the form of a plu- 90 rality of members of which there are two shown, being denoted respectively by 5 and 6. These members 5 and 6 are in the form of hollow cylinders or tubes, the inner tube or cylinder 6 being separated by, for in- 95 stance, a space 7 from the outer tube 5. Ordinarily the inner tube is rotatively adjustable to vary capacity. The outer tube 5 at its lower portion closely surrounds the disk 3. The cylinder or tube 6 is sustained 100 by the disk 3 and extends slightly above the cylinder 5.

The cylinders, structurally speaking and otherwise as a matter of fact, are virtually duplicates of each other so that a description of one will apply to the other. The cylinder 5 consists of an outer or enveloping part as 8 of paper stock, and an inner part 9 of tin-foil. While the paper stock 8 wholly incloses the tin-foil, this may not always be necessary. The paper and tin-foil are usually adhesively united in some con- 110

venient way. It will be seen, upon reference to Fig. 3, for instance, that the width or transverse extension of the tin-foil ply or sheet 9 is approximately equal to one-half 5 the circumferential extent of the tube 5. Although the paper stock wholly covers and incloses the tin-foil, this may not always be necessary. In this particular view the two 10 tin-foil portions are shown in exact registration or directly opposite each other, so that thereby I secure the maximum capacity of the condenser. By moving the tin-foil sheets out of register, the capacity of the condenser is reduced to zero; this capacity 15 may obviously be adjusted to any point from zero to the maximum, by turning the tube 6 within the tube 5.

A terminal as 10 is connected electrically with the tin-foil ply or sheet 9 of the outer 20 tube while a somewhat similar terminal as 11 is similarly connected with the tin-foil 25 ply or sheet of the inner tube 6.

To turn the inner tube 6 for regulation of capacity, any suitable means may be provided, for instance, that shown and now to 25 be described. In the upper end of the inner tube 6 is set a head 12, for example, of wood, through which is threaded the spindle 14 having at its upper end a manipulating 30 knob 15. By turning this knob the inner cylinder 6 may be likewise turned to adjust capacity.

The shank of a gage 16 may be fastened in some convenient way to the stationary or 35 fixed cylinder, the gage portion of the gage overhanging the head 12, and there being above it and coöperative therewith the pointer 17 fastened at its butt to the spindle or screw 14, the pointer, as the spindle is 40 turned, moving therewith and across the graduations 18 of the operative portion or scale of the gage member 16.

In Figs. 5 and 6 I show a flat construction. The base in this type is denoted by 20 45 and the elements or members of the active condensing portion by 21 and 22 respectively. In this kind of condenser the member 21 is practically of half disk formation, the member 22 being a complete disk. Said member 50 21 consists of superposed half disks 23 and 24 of paper and an interposed half disk sheet 25 of tin-foil, the tin-foil being so disposed between the paper sheets 23 and 24 that there will be a selvage or marginal portion of paper material entirely around the tin-foil. The adjustable member 22 of disk form is fastened to the spindle 26 supported for 55 turning movement by the base 20 and having a manipulating knob or finger piece 27 at its other end to facilitate its adjustment. Through the member 22 the spindle 26 fixedly extends. This member 22 consists as 60 shown of disks 23' and 24' and an interposed half disk 25' of tin-foil.

In Fig. 7 the condenser comprises members or elements as 30 and 31. These members or elements 30 and 31, except as to one point, to which I will later refer, are mounted and operated almost exactly like the members or elements 5 and 6 which I have 65 set forth so fully in detail. The supporting base is denoted by 32, the element 30 being rigid with it and the element 31 being turnable in the part 30 through the agency for example of the knob 33. These elements 30 70 and 31 are of tubular or hollow construction, the principal and in fact really the only difference between them and the parts 5 and 6 being that the parts 30 and 31 are of inverted frusto-conical form and are 75 not therefore cylindrical. In all three forms of the condenser it will be seen that the marginal portion of the paper, or equivalent material, overlies the foil so as to leave a margin or selvage of paper. 80

What I claim is:

1. A condenser comprising a plurality of coaxial relatively turnably adjustable elements each element being flexible and having insulating and conducting sections. 90

2. A condenser comprising relatively adjustable elements, each flexible and having insulating and conducting sections the insulating sections wholly inclosing the conducting sections. 95

3. A condenser comprising coaxial relatively adjustable elements, each flexible and having insulating and conducting sections, the respective conducting sections being wholly inclosed in the insulating sections 100 and the marginal portions of the respective insulating sections extending outward beyond the marginal portions of the conducting sections.

4. A condenser comprising coaxial relatively turnably adjustable elements, each of paper stock and metal foil. 105

5. A condenser comprising elements each of paper stock and metal foil and relatively adjustable to vary the capacity of the condenser. 110

6. A condenser comprising elements each of sheet paper stock and metal foil and relatively adjustable to vary the capacity of the condenser. 115

7. A condenser comprising tubular elements, one inclosed by another and each of paper stock and metal foil.

8. A condenser comprising tubular coaxial elements each of paper and foil and 120 relatively adjustable about their common axis.

9. A condenser comprising tubular elements, one inclosed by another and of paper stock and metal, the paper stock inclosing the metal foil and the marginal portions thereof extending outward beyond the marginal portions of the foil. the elements 125

being relatively adjustable about their common axis to vary the capacity of the condenser.

10. A condenser comprising spaced co-
5 axial tubular elements, one inclosed by an-
other, each of sheet paper and tin foil, the
sheet paper wholly inclosing the tin foil
and each of the paper portions of the ele-
ments extending outward beyond the mar-
10 ginal portions of the tin foil, the elements be-

ing relatively adjustable about their com-
mon axis to vary the capacity of the con-
denser.

In testimony whereof I affix my signature
in the presence of two witnesses.

CLARENCE D. TUSKA.

Witnesses:

LYDIA MATHER,
FREDERICK L. CLARK.
